UNITED STATES PATENT OFFICE.

THOMAS F. DUFF, OF SPOKANE, WASHINGTON.

LIFT-CAM ATTACHMENT.

Application filed August 9, 1924. Serial No. 731,129.

To all whom it may concern:

Be it known that I, THOMAS F. DUFF, a citizen of the United States, residing at Spokane, in the county of Spokane and State 5 of Washington, have invented new and useful Improvements in Lift-Cam Attachments, of which the following is a specification.

This invention relates to linotype machines and more particularly to a means to securely 10 and positively connect the lift cam to the distributor conveyor screw in such a manner that the lift cam may be quickly detached or adjusted.

A further object is to provide a lift cam 15 attaching means of the character specified which is of highly simplified construction, durable in use and cheap to install on machines either during the course of manufacture or at any time thereafter.

20 Other objects and advantages will be apparent during the course of the following description.

In the drawing forming a part of this application and in which like numerals are employed to designate like parts throughout 25 the same,

Figure 1 is a fragmentary elevation of a portion of the distributing mechanism equipped with the improved lift cam attachment;

Fig. 2 is a group perspective illustrating the lift cam attachment;

Fig. 3 is a fragmentary side elevation of the distributor screw or rear screw bar 35 equipped with the improvement in a slightly modified form, parts being shown in section;

Fig. 4 is a fragmentary perspective illustrating that the screw bar is quartered to 40 provide a plurality of partly severed members which are pressed into firm engagement with the inner wall of the lift cam by means of a tapered pin;

Fig. 5 is a perspective of a tool employed 45 for removing the tapered pin;

Fig. 6 is a fragmentary side elevation illustrating the lift cam secured in position by a slightly modified form of fastening means;

50 Fig. 7 is an enlarged detail sectional view illustrating the lift cam fastening device in position, the lift cam fastening device in this figure and in Fig. 6 being in the nature of a split washer held in position by a washer 55 expanding screw which engages the screw bar;

Fig. 8 is an elevation of the expandible washer and the washer expanding screw extended through the same;

Fig. 9 is a perspective of the washer which is adapted to expand into engagement with the wall of the opening in the lift cam.

In the drawing the numeral 1 designates a distributor box which has a channel through which the line of matrices M are fed to the upper and lower distributor screws 2 and 3 as each line comes from the casting mechanism. These matrices M are fed against shoulders 4 and 5 of the top and bottom rails 6 and 7 respectively of the distributor box.

The distributor lift operates to raise the matrices successively into engagement with the threads of the distributor conveyor screws a matrix being lifted at each revolution of said screws. The distributor lift, as shown 70 embodies an arm 8 which is pivoted at 9 and has a blade 10 which engages the bottoms of the matrices successively and thereby lifts the same into engagement with the conveyor screws. The arm 8 is operated by a lever 11, 75 the latter being provided with a roller 12.

Fig. 1 plainly illustrates that the roller 12 is engaged with the surface of a disk shaped cam 13, the cam being provided with a recess 14 by means of which the roller 12 is permitted to move inwardly at regular intervals and thereby bring about the operation 80 of the arm 8 and associated mechanism.

The invention forming the subject matter of this application resides in the means for securing the lift cam 13 and more particularly the attaching sleeve 15 of the same on the projection 16 of the screw bar 2. Fig. 2 plainly illustrates that the projection 16 is formed with a plurality of incisions 18 which define segmental portions 19 adapted to be received in the sleeve 15. The segmental portions 19 are freely received in the attaching sleeve 15 and are subsequently engaged by the wedge 22 by means of which the segmental portions 19 are securely and positively engaged with the inner wall of the sleeve 15.

The wedge 22 is in the nature of a flat strip of metal having laterally directed wings 25 and the forward portion of the strip of metal and the wings 25 are adapted to fit in the spaces between the segmental portions 19 and thereby support the segmental portions outwardly into firm frictional contact with the wall of the sleeve 15. This positively anchors cam 13 on the pro-

jection 16 and overcomes the necessity of employing separate fastening pins or keys.

The particular means illustrated for securing the cam 13 on the projection 16 permits the cam to be quickly detached for replacement or for readjustment when desired. It is merely necessary to engage the extended rear end of the wedge 22 with a suitable tool and forcibly detach the same. It will be seen that the extension on the rear end of the wedge is provided with an aperture 26 for the engagement of a small punch or the like by means of which the wedge may be quickly and forcibly withdrawn. When the wedge 22 is withdrawn from engagement with the projection 16 the cam 13 may be either replaced or adjusted circumferentially on the projection 16 to compensate for wear and thereby retighten the mechanism.

In the form of the invention illustrated in Figs. 3, 4 and 5 the screw bar is indicated by the numeral 30 and is provided with a projection 31 to which the sleeve 32 of the lift cam 33 is adapted to be adjustably connected.

Fig. 3 illustrates that the cam 33 is located somewhat beyond the quartered end of the projection 31 and a tapered pin 35 is adapted to be wedged between the quartered end of the projection so as to spread the segmental portions of the projection into firm engagement with the sleeve 32 so as to hold the sleeve in position.

A tool 36 is provided at its forward end with a forked portion 37 which may be engaged with the head 38 of the pin 35 as to forcibly withdraw the same when it is desired to renew or change the position of the cam 33. The tool 36 may be fulcrumed on the cam 33 when the forward end 37 is engaged with the head 38. In use the pin 35 may be hammered or otherwise forced into the space between the arms of the quartered forward end of the projection 31.

In the form of the invention illustrated in Figs. 6, 7, 8 and 9 the screw bar is indicated by the numeral 45 and the cam is designated by the numeral 46. Figs. 6 and 7 plainly illustrate that the cam 46 is provided with an attaching sleeve 47 designed to be secured upon the projecting end portions 48 of the screw bar 45. The projection 48 or extension 48 as the same may be said to be

is provided with a threaded socket 50 for the reception of a fastening screw 51. Fig. 7 illustrates that the attaching screw 51 is provided with a cone shaped head 52 adapted to be extended into the cone shaped bore of an extensible washer 53. The washer 53 is radially split and consequently when the screw 51 is advanced the washer is forced into firm engagement with the inner wall of the sleeve 47. It will be seen that the cone shaped head 52 has threaded engagement with the radially split extensible washer.

In the use of this form of the invention the sleeve 47 is mounted on the projection 48 and when the fastener 51 is threaded through the split washer 53 and into the projection 48 the washer is firmly wedged into engagement with the wall of the sleeve 47. This securely and positively holds the parts in position and at the same time permits the same to be quickly removed when it is desired to change the position of the cam or to renew the cam.

Having thus described the invention, what is claimed is:

1. In a linotype machine, the combination of a screw bar having one end provided with longitudinal incisions defining segmental portions, of a cam having a sleeve mounted on said screw bar and surrounding said segmental portions, and a wedge having a plurality of wings adapted to be positioned between the opposed sides of said segmental portions to move the segmental portions outwardly into engagement with the wall of the sleeve to form the sole means for securing the cam on the screw bar.

2. In a linotype machine, the combination of a screw bar having one end provided with longitudinal incisions defining segmental portions, of a cam having a sleeve mounted on said screw bar and surrounding said segmental portions, and a wedge having a plurality of wings adapted to be positioned between the opposed sides of said segmental portions to move the segmental portions outwardly into engagement with the wall of the sleeve to form the sole means for securing the cam on the screw bar, said wedge having a rearwardly projected apertured extension for engagement by a tool.

In testimony whereof I affix my signature. 105
THOMAS F. DUFF.
